UNITED STATES PATENT OFFICE.

THEODORE B. STAYNER, OF PROVIDENCE, RHODE ISLAND.

DESIGN FOR A WATCH CHARM OR PENDANT.

SPECIFICATION forming part of Design No. 19,102, dated May 14, 1889.

Application filed April 12, 1889. Serial No. 307,035. Term of patent 3½ years.

To all whom it may concern:

Be it known that I, THEODORE B. STAYNER, a citizen of the United States, residing at Providence, in the county of Providence and State of Rhode Island, have invented and produced a new and original Design for Charms or Pendants, of which the following is a specification, reference being had to the accompanying drawings, forming part thereof.

10 Figure 1 is a front view of a charm or pendant showing my design. Fig. 2 is a sectional view of the same on a perpendicular line through the center.

The leading feature of my design consists 15 in a circular rim projecting from the edge of the disk, forming the back of the charm or pendant, a central cylindrical projection, and two projecting rims concentric with the outer rim, forming part of a circle, the openings in 20 these rims being in opposite directions, as will be more fully set forth hereinafter.

In the drawings, *a* is the disk forming the back of the charm or pendant. *b* is the ring by which the same is secured 25 to a chain or band.

c is a raised rim projecting from the edge of the circular back *a*.

d is the central cylindrical projection.

e is a projecting rim forming part of a circle, leaving the opening *g* between the ends 30 of the rim *e*. The rim *f* also forms part of a circle, leaving the surface of the back plain at the space *h*. The spaces between the rims *c e f* and the central cylindrical projection, *d*, are of equal width, forming three concentric 35 spaces broken by the spaces *h* and *g*, which are placed in opposite directions.

What I claim is—

The design for a charm or pendant herein shown and described, the same comprising 40 the circular rim *c*, the rims *e* and *f*, each forming part of a circle, and the central cylinder, *d*, projecting from the back *a* and forming annular spaces united in pairs at the points *g* and *h*, the disk-shaped back *a*, and ring *b*, 45 as set forth.

THEODORE B. STAYNER.
